UNITED STATES PATENT OFFICE.

HANS THORMEYER, OF BERLIN, GERMANY.

INTERNAL-COMBUSTION ENGINE.

Application filed June 18, 1926, Serial No. 116,265, and in Germany May 28, 1925.

My invention consists in a compound internal combustion engine.

In the well-known compound internal combustion engines, there are large losses in heat, that is to say, in energy, because the intermediate connections between the high pressure stage and the low pressure stage must be thoroughly cooled in order to maintain a practicable working temperature and prevent injury to the engine parts by the hot exhaust gases, as overheating may render the engine unworkable. Moreover in the familiar engines the heat is not uniformly distributed throughout the whole system and thus stresses are set up in the material.

The present invention is an engine which aims to avoid said defects illustrated diagrammatically by way of example, in the accompanying drawing, in which Figs. 1 and 20 2 show the parts in different positions.

The engine as is usual comprises two four-stroke high pressure cylinders *a* and one two-stroke low pressure cylinder *b*.

The piston *c* of the low pressure cylinder 25 is stepped so as to form a cylindrical head and a disk-shaped portion. The hot exhaust gases from the high pressure cylinder, therefore, after mixing with the cool air admitted to the low pressure cylinder, strike the 30 upper head and the lower annular surface of the low pressure piston. The waste heat from the high pressure cylinders, as it escapes through the lower ports *d* and the upper valves *e*, is immediately distributed.

This is indicated in connection with one 35 of the high pressure cylinders on the left hand side in Fig. 1, while the admission of the supplementary charge into the high pressure cylinder is shown on the right hand side the working effect thereof being displaced through 360°.

In the illustration according to Fig. 1, the piston of the left high-pressure cylinder *a* has completed its working stroke, and the 45 combustion products are being exhausted through the ports *d*, which have been cleared by the piston. Because of this escape of the combustion products from the left high-pressure cylinder, a considerable increase in 50 pressure is produced in the low-pressure cylinder, which increase in pressure also is transmitted to the right high-pressure cylinder through the open ports *d*, with the result that the previously compressed charge 55 of fresh air in the right high-pressure cylin-

der is still further compressed, as the valve *e* in the right high-pressure cylinder has already been closed. In view of this increased compression of the fresh air charge in the right high-pressure cylinder, the exhaust gases from the left high-pressure cylinder can not enter the right high-pressure cylinder, the ports *d* of which are closed again, before the exhaust gases can travel the long distance from the left to the right high-pressure cylinder. These two cylinders are displaced as to their operation 360° relative to each other.

While during the next stroke, the piston in the left high-pressure cylinder in travelling upwards pushes the combustion products completely out of the cylinder through the open valve *e*, the piston in the low-pressure cylinder *c* travels downwards, during which stroke the energy of the exhaust gases is utilized in the low-pressure cylinder. During this time, the charge of fresh air in the low-pressure cylinder *c* which had previously been drawn into said cylinder through valve opening *h* is compressed. The piston in the right high-pressure cylinder also travels upwards compressing the fresh air charge in said cylinder. This position of the various pistons is shown in Fig. 2. Fuel is now injected into the right high-pressure cylinder—the fuel injection openings are indicated at *i* in Figs. 1 and 2—and as the charge is ignited by the heat of the compressed air, the piston in the high-pressure cylinder travels downwards. The 90 piston of the low-pressure cylinder meanwhile having reached its lower dead center, has thereby cleared the ports *f* and *g* so that the fresh air previously compressed by the descending piston now flows through the ports *f* into the low pressure cylinder scavenging the same and expelling the exhaust gases through the open ports *g*, as shown by the arrows in Fig. 2. The amount of this 95 fresh air is so large that as the ports *f* and *g* are closed again by the upward stroke of the piston, the low-pressure cylinder is only filled with fresh air. During the next stroke, therefore, the piston of the right high-pressure cylinder, because of the combustion therein, travels downwards, while the upwardly travelling piston of the low pressure cylinder compressing the fresh air in the low-pressure cylinder forces the same 105 into the left high-pressure cylinder through 110

110

the open valve *e*, at the same time cooling this valve, which previously had received the heat of the hot exhaust gases.

At the end of the working stroke of the 5 piston of the high-pressure cylinder, the ports *d* therein are opened, and the escaping exhaust gases again produce in the low-pressure cylinder a pressure increase, which is transmitted also to the left high-pressure 10 cylinder, the valve *e* of which, however, is closed, before the exhaust gases of the right high pressure cylinder have time to travel all the way from the right in Fig. 2 to the left. In a similar manner, the valve *e* of the 15 right high-pressure cylinder is opened only, after the pressure between the high-pressure and low-pressure cylinder has become balanced. The piston in the low-pressure cylinder by the exhaust gases from the right 20 high-pressure cylinder, is forced downwards, compressing the fresh air drawn in through valve *h* during the preceding upward stroke, the left high-pressure piston compressing the fresh air charge in its cylinder, into which thereupon fuel is injected 25 through the fuel opening *i*. Combustion

follows, and at the same time the right high-pressure cylinder receives a charge of fresh air, and the cycle commences again.

I claim:

1. A compound internal combustion engine comprising two high pressure engines and an intermediate low pressure engine, said low pressure engine including a stepped piston comprising a cylindrical portion and 30 a disk shaped portion, cylinders for said portions, a conduit connecting the said cylinders, an air intake port in the cylinder containing the disk shaped portion, an exhaust port in the cylinder containing said 35 cylindrical portion, and a valve in the cylinder of each high pressure engine receiving compressed air from, and exhausting products of combustion to, said conduit.

2. In combination with the structure 40 claimed in claim 1, a supplemental port in each high pressure cylinder communicating with said conduit at the end of the high pressure stroke.

In testimony whereof I have affixed my signature.

HANS THORMEYER.
